UNITED STATES PATENT OFFICE.

ALEXANDER K. SUTHERLAND, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

QUICK-BREAK SWITCH.

1,341,622.

Specification of Letters Patent. Patented May 25, 1920.

Application filed November 11, 1918. Serial No. 262,002.

To all whom it may concern:

Be it known that I, ALEXANDER K. SUTHERLAND, subject of the King of Great Britain residing at New Britain, Connecticut, have 5 invented a new and useful Quick-Break Switch, of which the following is a specification.

This invention relates to what are known as "quick break" switches.

10 The objects of the invention are to provide simple and effective mechanism for positively opening the switch and for securing a quick separation of the contacts at the moment of interrupting the circuit.

15 Briefly stated the invention resides in the combination with the movable switch element and the operating member therefor, of a positive lost motion connection between the operating member and switch member 20 including pivoted links having lost motion engagement with one of said parts and a spring connection for normally taking up such lost motion.

25 A special feature of the invention is the connection of the lost motion links directly with the switch blades so as to get a direct straight pull on the switch blades and a further feature of invention is the making of these connecting links of insulating material to prevent conduction of current from the switch blades to the switch operating member.

30 Other features of the invention will appear as the specification proceeds.

35 In the accompanying drawing I have illustrated the invention embodied in a practical commercial form but it will be understood that changes and modifications such as come within the scope of the appended 40 claims may be made without departure from the true spirit of the invention.

In said drawing:

Figure 1, is a top plan view or front view of a switch having the features of the invention incorporated therein.

45 Fig. 2, is a cross sectional view of the same taken substantially on the plane of the line 2-2 of Fig. 1.

50 In the construction illustrated, the movable element of the switch is made up of a plurality of switch blades 5 pivoted at 6 and arranged to engage the contacts or clips 7. The free ends of said switch blades are connected in substantial parallelism by a

cross bar 8 usually made of insulating material, as shown.

The operating member for the switch consists in the disclosure of a handle 9 pivoted at 10 in substantial alinement with the switch pivot 6 and having an oscillating operating arm 11.

The lost motion connections between the operating arm and the switch blades consist of the links 12, having in the illustration, pivotal connection with both the switch 65 blades and the operating arm. As shown, the connection with the switch blades at one end is a plain pivotal connection 13 and at the opposite end the links are slotted as indicated at 14 to receive the operating arm 70 11 and provide both a pivotal connection 15 and a lost motion engagement between the links and the operating arm.

In the construction illustrated, the links are arranged in pairs, one at each side of 75 each switch blade. This equalizes the pull on each switch blade, the force being thereby applied directly in line with the switch pivots and contact clips. This makes a smooth, easy action and avoids any binding 80 of the parts.

In view of the fact that the operating links are directly connected with the switch blades, I prefer to construct said links of insulating material so as to prevent conduction 85 of current from the switch blades to the operating member. These links may be cut from flat sheets of insulating material, being punched to shape with the pivot hole in one end and the longitudinal slot in the 90 opposite end. A single rivet at the pivot point 13, suffices to hold each pair of links together at the opposite sides of a switch blade.

A yielding connection is provided between the operating member and movable switch element, the same consisting in the disclosure of a plurality of coiled springs 15 connected between the cross bar 8 and the operating arm 11.

95 From the foregoing description it will be seen that upon rocking the handle in a switch opening direction the operating arm will be carried to the farthest or outer end of the slots in the links, providing a positive connection between the operating arm and switch blades, incidentally placing the springs 15 under tension. As the switch 100 105

handle is further moved, the switch blades will be shifted by the positive connection described and just as the blades are about to leave the relatively stationary contacts, 5 (Fig. 2) the spring connections will react and snap the blades quickly out of engagement with the stationary contacts, the lost motion referred to allowing for this snapping movement of the blades independently 10 of the movement of the operating member 11.

The quick break movement is further assisted in the present disclosure by the switch opening spring 16 which is shown anchored 15 at one end at 17 to a relatively stationary support and connected at its opposite end with the operating arm 11. The tendency of this spring is to throw the switch as soon as the movement of the handle is started, to 20 the full open position.

I claim:—

1. In a switch of the character described, a plurality of stationary posts, switch blades pivoted thereto, a plurality of contacts, a cross bar connecting said blades, a rocking switch operating arm, insulating links pivoted at one end to the switch blades and having an elongated slot at the other end for engagement with the operating arm 30 and a spring connected at opposite ends with the operating arm and the cross-bar.

2. In an electric switch, a series of stationary contacts, a series of posts, switch blades pivoted to said posts and adapted to engage said contacts, an insulating cross bar connecting said blades, a swinging operating arm, and an insulating link pivotally connecting each blade with said arm.

3. In an electric switch, a series of sta-

tionary contacts, a series of posts, switch blades pivoted to said posts and adapted to engage said contacts, an insulating cross bar connecting said blades, a swinging operating arm, an insulating link connecting each blade with said arm, and a spring connecting said insulating cross bar with said arm.

4. In an electric switch, a stationary contact, a post, a blade hinged to said post and adapted to engage said contact, a swinging operating arm and a slotted link connecting said blade and said arm formed of two pieces of insulating fiber with the blade secured between the same, and a spring for moving said blade in one direction with a snap action.

5. In an electric switch, a stationary contact, a post, a blade hinged to said post adapted to engage said contact, a swinging operating arm and a link connecting said blade and said arm formed of two pieces of insulating fiber with the blade secured between the same, said pieces of fiber having elongated slots to allow the operating arm and blade to have relative independence of motion.

6. In a switch of the character described, a plurality of posts, a plurality of contacts, a movable switch member including switch blades pivoted to said posts and a bar connecting said blades, a swinging operating arm, a lost motion connection between said arm and each of said blades, and a spring connecting said arm and switch member for throwing the switch member to open circuit position with a snap action.

ALEXANDER K. SUTHERLAND.
